DESIGN FOR A HANDBAG

Alex Glaser, Paris, France, assignor to Richard Alan Inc., a corporation of New Jersey

Application May 28, 1946, Serial No. 130,183

Term of patent 3½ years

(Cl. D87—3)

To all whom it may concern:

Be it known that I, Alex Glaser, a citizen of the Republic of France and a resident of Paris, Seine, France, have invented a new, original, and ornamental Design for Handbag, of which the following is a specification, reference being had to the accompanying drawing, forming a part thereof.

The cross shading is used to indicate a contrasting color.

I claim:

The ornamental design for a handbag, as shown and described.

ALEX GLASER.
